(57) **CLAIM**

The ornamental design for a watch case as shown and described.

DESCRIPTION

FIG. 1 is a perspective view of a watch case of the present invention;

FIG. 2 is a front view of the present invention shown in FIG. 1;

FIG. 3 is a rear view of the present invention shown in FIG. 1;

FIG. 4 is a left-side view of the present invention shown in FIG. 1;

FIG. 5 is a right-side view of the present invention shown in FIG. 1;

FIG. 6 is a top view of the present invention shown in FIG. 1;

FIG. 7 is a bottom view of the present invention shown in FIG. 1;

FIG. 8 is a perspective view of a second embodiment of a watch case of the present invention;

FIG. 9 is a front view of the present invention shown in FIG. 8;

FIG. 10 is a rear view of the present invention shown in FIG. 8;

FIG. 11 is a left-side view of the present invention shown in FIG. 8;

FIG. 12 is a right-side view of the present invention shown in FIG. 8;

FIG. 13 is a top view of the present invention shown in FIG. 8;

FIG. 14 is a bottom view of the present invention shown in FIG. 8;

FIG. 15 is a perspective view of a third embodiment of a watch case of the present invention;

FIG. 16 is a front view of the present invention shown in FIG. 15;

FIG. 17 is a rear view of the present invention shown in FIG. 15;

(Continued)

FIG. 18 is a left-side view of the present invention shown in FIG. 15;
 FIG. 19 is a right-side view of the present invention shown in FIG. 15;
 FIG. 20 is a top view of the present invention shown in FIG. 15; and,
 FIG. 21 is a bottom view of the present invention shown in FIG. 15.
